SOUND RECORDER AND REPRODUCER

Raymond Spilman, New York, N. Y., and Henry S. Jones, Stamford, Conn., assignors to J. C. Warren Corporation, Freeport, N. Y., a corporation of New York

Application November 20, 1953, Serial No. 27,686

Term of patent 7 years

(Cl. D26—14)

FIG. 1

To all whom it may concern:

Be it known that we, Raymond Spilman and Henry S. Jones, citizens of the United States and residents, respectively, of New York, county and State of New York, and Stamford, county of Fairfield, State of Connecticut, have invented a new, original, and ornamental Design for Sound Recorder and Reproducer, of which the following is a specification, reference being had to the accompanying drawing, forming a part hereof, wherein

We claim:

The ornamental design for a sound recorder and reproducer, as shown.
